MERCURY SWITCH

Carl J. Warnke, Elkhart, Ind., assignor, by direct and mesne assignments, to The Adams & Westlake Company, Chicago, Ill., a corporation of Illinois

Application February 1, 1932, Serial No. 590,002

2 Claims. (Cl. 200—152)

My invention relates to mercury switches or sealed containers in general, and is concerned more particularly with providing a device of this character in which the outer envelope or container is protected against the ordinary disintegrating influences present in the operation of the switch.

One object of my invention is to devise a mercury switch which is constructed and arranged to materially shorten the length of the current path through the switch with a view of correspondingly reducing the electrical resistance and accompanying heat effects which would otherwise obtain owing to the relatively low conductivity of mercury.

A further object is to provide a switch of the type comprising an outer envelope and an inner structure disposed in spaced relation thereto and sealably connected to provide an integral unit characterized by strength and rigidity, the inner structure substantially dividing the outer envelope into two chambers and having a ceramic sleeve attached thereto composed of arc resisting material that readily permits the switch to be employed under high wattage conditions.

A further object is to devise a switch of the character described in which the ceramic sleeve is preferably composed of a material, such as zirconium oxide or an equivalent substance, which is characterized by a melting point several times that of glass and a coefficient of thermal expansion substantially equal to that of glass, thus protecting the switch against the erosive conditions usually obtaining and permitting the sleeve to be attached to the inner tube without creating any internal strains arising from heat effects under conditions of operation.

A further object is to provide a switch as above set forth which is characterized by a mercury to mercury contact owing to the interposition of the inner tube which insures a merging and dividing of the mercury mass in the circuit making and breaking positions of the switch, respectively, and consequent lengthening of the operative life of the electrodes since they are not subjected to the erosive effects of the electric arc.

A further object is to provide a mercury switch which incorporates the above noted advantages and which is further simply constructed and arranged to withstand the rigors of daily operation over a long period, and whose manufacture is comparatively inexpensive and susceptible of being practiced under large scale manufacturing conditions.

In the operation of a mercury switch whether

employing a mercury to metal contact or a mercury to mercury contact, when the electrical circuit is interrupted or is about to be completed by an appropriate actuation of the switch container, the tendency of the current to break down the dielectric strength of the intervening air or gas gap results in the creation of an electric arc of relatively high temperature which has a marked capacity for effecting deterioration of the elements of which the switch is composed, the periodic impingement of the arc upon the glass of the envelope in the region adjacent the rupture of the electrical circuit frequently causes a breakdown of the glass at the indicated point. This condition is particularly aggravated where a mercury switch is employed in an inductive circuit owing to the high voltage arc which is induced at the breaking of the circuit and the resulting rapid changes of temperature which subsequently are obtained within the switch envelope. This rise in temperature occurs within a relatively short period of time, as does the temperature recession downwardly therefrom to the normal temperature of the switch, so that the glass envelope is subjected to a highly destructive effect in both instances, the glass being actually eroded with a consequent decrease in the wall thickness, so that excessive stresses are established in the envelope which are in addition to and superimposed on the actual stresses present in the glass. The glass accordingly breaks at the indicated point and the switch is therefore removed from service. Similar rapid temperature changes occur in induction switches when employed in circuits which are subject to high current surges, that is in inductive circuits through which the current flows intermittently and in which the loads are heavy, such as the lamp banks of advertising signs and similar installations.

Many structural solutions have been heretofore proposed as remedies for the above disadvantages, one such type proposed being in the nature of an outer envelope which encloses an inner, protected structure which alone is subjected to the ravages of the electric arc and which is therefore especially constructed to resist the same. It is accordingly possible to make both the outer envelope and the inner structure of a cheaper material and one that is less expensive to work during the manufacturing operation, while particularly treating the inner structure to effectively resist the high temperature conditions obtaining. The switch comprising the present invention belongs generically to the latter type of mercury switch, but in addition embodies cer-

tain specific advantages as regards the relative locations of the inner structure, the mercury mass, and the electrodes, which are so disposed as to provide a considerably shorter path for the 5 electric current when the switch is in a circuit making position, than now obtains generally in the art. Mercury is characterized by a relatively high resistance and by so disposing the above parts in the manner indicated, it is possible to 10 minimize to a considerable extent the low conductivity of the mercury, as well as protecting the glass and the electrodes against the ravages of the electric arc.

These and further objects of my invention will 15 be set forth in the following specification, reference being had to the accompanying drawing, and the novel means by which said objects are effected will be definitely pointed out in the claims.

20 In the drawing:

Figure 1 is a sectional elevation showing my improved switch in circuit breaking position.

Figs. 2 and 3 are views similar to Fig. 1, but 25 showing the switch in two different, circuit making positions.

Fig. 4 is a perspective view of the ceramic sleeve utilized in my improved switch to protect the glass structure against erosion.

The switch shown in the drawing is intended 30 merely as illustrative of switches of this general character and it will be understood that the details of construction may be modified as appears desirable, dependent upon the external shape of the switch container, the disposition and number of the lead-in conductors employed, and miscellaneous other factors.

Referring to Fig. 1, the switch comprises an outer envelope or container 10 which may be composed of soft glass or any other suitable material that is customarily employed in the manufacture of mercury switches and in the type shown has a generally elongated shape, although the precise nature of the latter forms no part of the present invention. However shaped, the 45 container 10 will have positioned therein an inner element or structure 11 which is shown as tubular in conformation, although it may assume other forms, and is preferably composed of the same kind of glass as is the outer envelope 10. The 50 tube 11 is preferably concentrically disposed with reference to the envelope 10 and at one end thereof is fusibly connected with said envelope by means of an annular wall 12, thus dividing the interior of the envelope 10 into chambers 13 and 55 14 which have communication through the tube 11. The opposite end of said tube terminates short of the adjacent end wall 15 of the envelope 10 and the opposite end wall 16 may be pinch-sealed during the manufacture of the switch in 60 the usual manner in order to hermetically seal the envelope.

Positioned within the open end of the tube 11 is a ceramic sleeve 17 having an annular shoulder 18 which abuts against the end edge of the sleeve 65 11. The sleeve 17 is fused or sealed, or attached in any other convenient manner to the inner tube 11 and is preferably composed of zirconium oxide, or an equivalent material which has substantially the same coefficient of thermal expansion as the 70 glass composing the tube 11. This sleeve, when composed of the indicated material or materials, is characterized by a melting point which is from three to five times that of glass or, generally speaking, is considerably higher than the latter, so that it is well adapted to withstand rapid tem-

perature changes, as well as the deteriorating effects of the electric arc. Extending through the end wall 15 are electrodes 19, 20 and 21, electrode 19 being substantially axially aligned with the inner tube and projecting within the ceramic sleeve 17, with the other electrodes disposed above and below the electrode 19 in the form of construction shown in Fig. 1. The electrodes may be of any desired shape and material and are connected externally of the envelope by means of lead-in conductors of the customary type which are sealed through the end wall 15 in a manner to prevent leakage at these points.

80 In the circuit breaking position of the switch, as shown in Fig. 1, the chamber 13 encloses a mass of mercury 22 which is located entirely to the left of the sleeve 17, while the chamber 14 carries a mass of mercury 23 in which is continually immersed the electrode 21. The arrangement of the several parts of the switch is such that, when the envelope 10 is tilted into the position shown in Fig. 2, the electrical circuit is completed through the switch by a uniting of the mercury masses 22 and 23 over the surface presented by a portion of the sleeve 17. Similarly, when the envelope 10 is returned to the position shown in Fig. 1, the then single mass of mercury divides substantially over the same surface to form the separate masses 22 and 23, thus 95 breaking the electrical circuit. It will be particularly observed that, when the switch is moved to a circuit making position, the mercury mass 22 establishes contact with the electrode 19 prior to joining with the other mercury mass 23, and, similarly, when the switch is moved to a 100 circuit breaking position, the division of the single mercury mass occurs prior to the separation of the mercury mass 22 from the electrode 19. Accordingly, such sparking as may occur will be substantially directed against the specially formed 105 sleeve 17 which along is subjected to the erosive action obtaining during these operative phases of the switch.

Referring to Fig. 2 which shows one circuit 110 making position of the switch, it will be noted that the length of the current path between the electrodes 19 and 21 is substantially determined by their distance apart, a factor which is susceptible of variation as may be desired to obtain any required length of path with a view of minimizing the relatively low electrical conductivity which characterizes mercury. Resistance losses within the switch are therefore considerably lessened as well as the heat effects which flow from such a condition. The switch is therefore capacitated for use more particularly under conditions 115 requiring the carrying of a relatively high amperage which renders the switch highly advantageous for use under heavy load conditions. The switch is further characterized by a relatively long 120 life, particularly as regards the substantial freedom of the glass composing the principal portion of the switch from erosion and the avoidance of any tendency of the electrodes to become pitted.

125 The switch is illustrated as being provided with the extra electrode 20 in order to enable it to be employed under conditions wherein the switch substantially occupies the position shown in Fig. 3 under circuit making conditions, wherein the electrode 19 and its inlead wire may serve as a 130 common return for the electrodes 20 and 21 and their inlead wires. Where it is contemplated that the switch will occupy the circuit making position shown in Fig. 2, the addition of the electrode 20 further avoids the likelihood of any 135 ruis-

- take on the part of the mechanic installing the switch arising from uncertainty as to whether the switch should be so positioned as to place the electrode 20 above the electrode 19 or vice versa. 5 The electrode 20 enables the switch to be placed either in the position shown in Fig. 1, or in a position in which the electrode 21 occupies the position shown by the electrode 20 without affecting in any way the normal operation of the switch.
- 10 While I have shown one set of elements and combinations thereof for effectuating my improved mercury switch, it will be understood that the same is intended for purpose of illustration only and in no wise to restrict my device to the 15 exact forms and structures shown, for many changes may be made therein without departing from the spirit of my invention.
- I claim:
- 20 1. In a mercury switch, a glass envelope, spaced conductors sealed through one end of the envelope, a glass tube secured within the envelope adjacent to the other end thereof, a mass of mercury cooperating with the conductors to make or break an electrical circuit according to the 25
- position of the switch, the inner projecting ends of said conductors being arranged so that the mercury mass will divide over the free end of the tube to break the electrical circuit and will substantially cover the conductors adjacent to their seals when the circuit is closed, whereby heat within the conductors is dissipated by the mercury.
2. In a mercury switch, a glass envelope, spaced conductors sealed through one end of the envelope, a glass tube secured within the envelope adjacent to the other end thereof, a mass of mercury cooperating with the conductors to make or break an electrical circuit according to the 30 position of the switch, the inner projecting ends of said conductors being arranged so that the mercury mass will divide over the free end of the tube to break the electrical circuit and will substantially cover the conductors adjacent to their seals when the circuit is closed, whereby heat within the conductors is dissipated by the mercury, and a refractory sleeve at the free end of the tube.
